UNITED STATES PATENT OFFICE.

JAMES ALBERT HOGG, OF LOWELL, MASSACHUSETTS, ASSIGNOR TO C. G. SARGENT'S SONS CORPORATION, A CORPORATION OF MASSACHUSETTS.

DRIER.

Application filed June 9, 1923. Serial No. 644,473.

To all whom it may concern:

Be it known that I, JAMES ALBERT Hogg, a citizen of the United States, residing at Lowell, in the county of Middlesex and 5 State of Massachusetts, have invented a new and useful Drier, of which the following is a specification.

This invention relates to a drier capable of general use but particularly for drying 10 fibrous materials such as wool, cotton and the like.

The principal object of the invention is to provide for increasing the drying capacity of a machine of this kind and improving 15 the product by subjecting the material to a preliminary drying operation, and the modification of the drier to permit of the location of the feeding device within the drying chamber, or in such close communication therewith that the heated air currents from the drier proper will permeate the 20 fibrous material while being fed forward toward the drying apron. Further objects and advantages of the invention will appear 25 hereinafter.

Reference is to be had to the accompanying drawings in which—

Fig. 1 is a side elevation of a wool drying machine constructed in accordance with this 30 invention;

Fig. 2 is a plan of a portion of the same on enlarged scale;

Fig. 3 is a longitudinal sectional view on the line 3—3 of Fig. 2; and

Fig. 4 is a transverse sectional view on the line 4—4 of Fig. 2.

I have shown the invention as applied to a well known type of wool drying machine involving a casing 10, drying apron 11 on 40 which the material is conducted through the machine, and coils 28 of steam pipes arranged at different places with blowers 14 for circulating the air. This machine of course has other features, some indicated in 45 the drawings, but not specifically described herein because they do not constitute part of this invention, and because the invention is capable of being used without them.

Heretofore it has been customary to provide 50 a separate automatic feeding machine set up at the intake end of the drier for loosening up the material and continuously feeding it on the drier apron in a loose state. This material of course is laden with

moisture and the drying does not commence 55 to take effect in the old machines until the material is deposited by the feeding device on the apron.

In this invention I extend the side walls of the casing 10 rearwardly far enough to 60 enclose the automatic feeding machine and provide the extended end with a door 15 through which the material can be dumped in as appears through the glass panel 16 in Fig. 1, and I also preferably provide an inlet pipe or opening 17 through which the material can be fed in by a blowing system or conveyor so that the material can be introduced in either of these ways if desired. 65

Inside this end of the machine is a feeding device comprising a horizontal endless apron 20 on which the material is deposited and an inclined feeding apron 21 located adjacent thereto at the lower end for taking the material up over the upper roll and past 70 the comb 22. This draws the material up over the upper roll against the usual beater 23 and it is deposited on the apron 11 in front of the baffle plate 24.

These parts just described are operated in 75 any desired way by power and are located within the casing 10 at the end of the apron 11 as indicated. I have illustrated one kind of automatic feed, but this invention is not limited to that particular type of feeding 80 device.

The casing can be extended upwardly if desired to accommodate a higher feeding device. I also preferably use baffle plates 26 and partitions 27 to concentrate the currents 90 of air which are introduced by the several blowers 14. It is customary to have the steam coils for heating purposes along one or both sides of the drier, and I have shown the ordinary coils 28 and an extra coil 29 95 located at the end of the same. This extra coil need not always be used, but it increases the drying capacity of the device, especially as the blower adjacent thereto blows the heated air in directly against the material 100 as it is fed into the machine and even while it is piled up on the apron 20 and also forces currents of air through it as it is passing up to the top of the machine by the action of the apron 21. The baffle plates 26 can 105 be adjusted to control the air currents if desired.

In front of the coils of pipes I have shown

two screens 30 for keeping the material out of the heating coils and confine it to the space occupied by the feeder. The direction of the air currents is indicated by the arrows and it will be seen that they pass all around through the material as far as they can. The material on the outside of the pile dumped on the apron 20 is always exposed to the currents of heated air and as 10 this is worked over and over all parts of it are subjected to the drying at this point.

After the material is deposited on the apron 11 it is subjected to the same drying action that is possible in the old constructions preferably, although if desired, and if the material comes out dry enough at the delivery end of the drying apparatus in some cases this part of the device can be shortened.

20 In this way the material to be dried is subjected to a preliminary drying action while it is being fed into the ordinary drier and large amounts of moisture can be extracted while the material is traveling to the apron 25 11 and removed before it reaches it. Thus the drying action is rendered much more efficient than heretofore and also more rapid.

I do not limit myself, except as expressed in the claims, to the details of a unitary 30 structure for a drier and feeding device.

Although I have illustrated and described only a single form of the invention I am aware of the fact that modifications can be made therein by any person skilled in the 35 art without departing from the scope of the invention as expressed in the claims. Therefore I do not wish to be limited to all the

details of construction herein shown and described, but what I do claim is:

1. A drier for fibrous material having a 40 casing, an endless apron therein for carrying the material, means for circulating heated air through the drier, and means located in the drier casing in communication with said air currents for separating the 45 fibrous material from a quantity of material in bulk, spreading it out, and depositing it in a continuous manner on said apron, whereby the drying of the material will be going on while it is being separated, spread 50 out and fed to the apron.

2. The combination with a drier having means for conveying material to be dried, and means for heating the air in the drier, of a feed apron within said drier and in position to be subjected to the influence of currents of heated air therein for preliminarily drying the material before it is deposited on the conveying means, and a blower in position to force a current of 60 heated air directly against the material where it enters the machine.

3. The combination with an endless drier apron for carrying the material to be dried through a drier and an automatic feeding device for feeding the material to be dried in a continuous manner, of means for heating the air in the drier and means for forcing currents of the air directly against and through the material while it is being fed 70 to the apron.

In testimony whereof I have hereunto affixed my signature.

JAMES ALBERT HOGG
